W. F. JONES

CONCRETE FENCE

Filed Nov. 13, 1920

Inventor:
William F. Jones.
By *Frank J. Hanson*,
Attorney.

UNITED STATES PATENT OFFICE.

WILLIAM F. JONES, OF ST. LOUIS, MISSOURI.

CONCRETE FENCE.

Application filed November 13, 1920. Serial No. 423,950.

To all whom it may concern:

Be it known that I, WILLIAM F. JONES, a citizen of the United States, residing in the city of St. Louis and State of Missouri, have invented certain new and useful Improvements in Concrete Fences, of which the following is a specification.

My invention relates to fences constructed of concrete, preferably reinforced, and has 10 for its object to provide a concrete fence which will be strong, durable and of relatively low cost.

A further object of the invention is the provision of a concrete fence which is 15 formed of separately molded sections that can be readily and easily assembled by a single person.

A further object of the invention is the provision of a fence which will be as strong 20 as a monolithic structure and which possesses the special advantages of being quickly erected, or taken down, without injury to the several parts constituting the fence.

With the above and other objects in view, 25 the invention consists in the novel features of construction, arrangement and combination of parts hereinafter described and finally pointed out in the claims hereto appended.

Referring to the accompanying drawings 30 forming a part of this specification wherein like characters of reference denote similar parts throughout the several views:

Fig. 1, is a view partly in elevation and 35 partly in cross-section of a section of a fence constructed in accordance with my invention.

Fig. 2, is a sectional view taken on line 2-2 of Fig. 1.

Fig. 3, is a detail in perspective of the 40 sill member.

Fig. 4, is a sectional view in perspective, 45 of the sill member taken on line 4-4 of Fig. 3.

Fig. 5 is a sectional view in perspective 50 of the top rail member.

Fig. 6, is a view of the fence taken on 55 line 5-5 of Fig. 1.

Referring to the drawings, the reference 60 character 1 designates suitable concrete fence posts. 2 indicates a plurality of longitudinal reinforcing rods molded in the posts. Each post 1 is provided near its upper end with a pair of suitably spaced strap iron 65 supporting members 3 to form a socket 4

on opposite sides of each post 1. Each post 1 is further provided near the ground line thereof with a pair of suitably spaced strap iron members 5 to form a socket 6 on opposite sides of each post 1. Each end 60 of the strap members 3 and 5 is provided with aligned slotted openings 7.

8 indicates an upper concrete rail member which is reinforced by means of longitudinal rods 9. Each end of the rail member 8 is provided with an additional embedded reinforcing member in the form of a strap iron member 10 to add strength to each end of the rail member 8. Each end of the rail member 8 is further provided with a plurality of vertically disposed openings 11 through which bolts 12 pass for securing the ends of the rail member 8 in the sockets 4 formed by iron members 3. It will be observed that the slotted 75 openings 7 in the strap iron members 3 and 5 will permit of contraction and expansion to take place without injury to the ends of the rail 7.

A concrete sill member is employed 80 which consists of a front board like section 13 and a right angular rail like section 14 which is formed at the upper end of the board like section 13. The two sections 13 and 14 are strengthened by means 85 of the concrete filler rib 15. The upper face of the board like section 13 of the sill member is provided with a plurality of suitably and equally spaced depressions, or seats 16, which seats are separated by 90 means of the concrete walls 17. The sill member is provided with longitudinal reinforcing rods 18 which are embedded in the board like section 13 and with longitudinal reinforcing rods 19 which are embedded in rail like section 14. Vertical reinforcing rods 20 are also employed, which are embedded in the board like section 13, the walls 17 and terminate in the rail like section 13 of the sill member, as clearly 100 shown in Fig. 4.

Each end of the board like section 13 of the sill member extends slightly beyond the end faces of the rail like member 14 of the sill member, as at 21, and are provided with the slotted openings 22. The extended ends 21 of the board like section 13 engage the front face of the posts, while the ends of the rail like section 14 are receivable in the sockets 6 formed between 110

the strap member 5. The sill member is secured to the posts 1 through the strap 5 by means of the bolts 23 and 24, respectively. The openings in the strap members 5 being slotted, permit the rail sections to contract and expand longitudinally, as is manifest.

25 indicates suitable concrete board members, which may be of any desired length, 10 width, or design. For illustrative purpose only, I have shown the board members as rather wide and provided with a longitudinal opening 26 to reduce the weight thereof and to add to the design of the fence. 15 The concrete boards are provided with longitudinal reinforcing rods 27 and with transverse reinforcing rods 28 at each end thereof, as shown in Fig. 1.

The lower ends of the concrete boards 25 20 are seated in the seats 16 of the sill member, which properly spaces the boards. The boards 25 are removably fixed to the upper rail members 3 and the rail like section 14 of the sill member by means of bolts 29 and 25 30, respectively, or any other suitable fastening means.

The board members 25 which are used at the posts, are preferably provided with slotted openings 31, through which the bolts 30 pass to permit of expansion and contraction 35 of the fence, as is manifest.

From the foregoing description, it will be readily seen that I provide a concrete fence, which will be neat and attractive in 35 design and appearance, strong, durable, and not effected by the elements, and a fence which can be easily and quickly assembled, or taken down by one man.

The many advantages of the herein described invention will readily suggest themselves to those skilled in the art to which 40 it appertains.

I do not wish to be understood as having limited myself to the specific details of construction shown and described, but desire 45 to have it understood that the invention I have shown in the drawings is merely illustrative, as it is manifest that various minor changes may be made in the exact construction 50 and particular arrangement of several parts without departing from the spirit of my invention, hence I reserve the right to make any such changes, or modifications as may fairly fall within the scope of the appended claims when fairly construed.

What I claim is:

1. In a fence structure, in combination 55 with a supporting post having spaced laterally extending metallic supporting members which pass through the post and are

arranged in pairs one above the other and provided with aligned slotted openings, concrete rails carried by said metallic supporting members and secured at their end therebetween by means of bolts, the lower rail 65 of the two being right angular in cross section and having its front upright wall extending beyond the ends of the upper horizontally disposed section of the lower rail 70 for engagement with the front face of the post and provided with slotted openings for receiving fastening devices anchored in the post, seats formed along the outer corner edge of the lower rail and spaced apart by ribs, concrete fence board members removably secured to the upper and lower rails 75 and the board member applied to the rails opposite the post having slotted openings therein to receive fastening devices anchored in the rails. 80

2. A fence of the class described comprising, in combination, reinforced concrete posts suitably spaced apart, horizontally disposed metallic supporting members embedded in the posts and arranged in pairs 85 and in suitable spaced relation and extending beyond opposed faces of the post and said extended ends being provided with aligned slotted openings, an upper reinforced concrete rail member having each 90 end provided with a metallic strengthening plate disposed between two posts, the ends of said rail being carried by means of the paired upper metallic supporting members and secured thereto by means of bolts, a 95 lower rail member having a board like front section and an upper right angularly disposed sill section, said sill section being disposed between two posts, the ends of said sill section being carried by means of the 100 paired lower metallic supporting members and secured thereto by means of bolts, the board like section of said lower rail having its ends extending beyond the ends of the 105 sill section and provided with slotted openings, said extended ends of the board like section being secured to the front face of two posts by means of bolts, spaced seats formed along the upper face of the board like member of the lower rail and reinforced 110 concrete upright board members removably fixed to the upper rail member and the sill section of the lower rail member and the lower ends of said board members being positioned upon the seats of the lower rail 115 section.

In testimony whereof, I have hereunto signed my name to the specification.

WILLIAM F. JONES.
